ARTHUR T. KARR, OF YAKIMA, WASHINGTON.

LUMP-COAL OR COAL-BRIQUETTE BURNING ORCHARD HEATER.

Application filed February 18, 1926. Serial No. 89,080.

My invention relates to a lump coal or coal briquette burning orchard heater. More particularly, my invention relates to a heater of a character suitable for use in fruit orchards 5 to provide heat for the protection of the orchard against damage by frost or freezing.

Serious objection obtains to the solid fuel type of orchard heater having grates, in that the cost in the first instance is high and the 10 care incident to operating such heaters is likewise expensive and onerous. In a small orchard of ten acres an operator may have in charge as many as five to seven hundred such heaters, and since the fuel tends to form a 15 crust and bridge across the heater, it requires the use of a poker to break this down and as the heaters are usually in operation during the night, such attention involves the loss of much time. Some of such type of heaters 20 have a cover as the means of regulating the rate of burning, but such are highly objectionable on account of the great amount of time required to operate.

The uncertainty and suddenness of a drop 25 in temperature presents the condition to be satisfied of quickness of attaining effective heating combustion after lighting, particularly when the sap in the trees is running. A few minutes of exposure may cause injury 30 to, or loss, of the the crop for that year, amounting to thousands of dollars. The coldest part of the night ordinarily comes just before sunrise, and it is common practice then to have a force of operators on hand 35 who are constantly watching the temperature, and upon a fall of the same below the safety point, their duty is to proceed in great haste to light the heaters throughout the orchard, which may often involve a number 40 of acres and therefore many hundreds of heaters, and effective heat must be immediately forthcoming. Since only a small drop below the critical temperature is sufficient to do serious damage, weather reports cannot be 45 relied upon.

The period during which the heater must continue in operation is generally from one to five hours or more, and hence the heaters must be so designed that the rate of burning 50 of the fuel may be carefully regulated. Me-

chanical devices, such as drafts or dampers, are not practicable, and the regulation of the burning should be automatic.

The heat must not be intense in the heater, as the same is most economically constructed 55 of sheet metal and a high temperature obviously would quickly burn out such metal, and the fruit itself requires a uniform temperature. Any great heat at one point would tend to over-heat the orchard in that immediate locality, and hence small fires, properly spaced, are a fundamental requisite. The number per acre cannot be much less than approximately forty, for otherwise the fires would be too big and too far apart. Hence 60 65 this imposes the condition for a large number of heaters, and hence the manual attention to each must be reduced to a minimum for a successfully operating orchard heater.

To provide convenience of operation, a 70 solid fuel heater suitable for use in the orchard should be capable of being lighted from the top, so that a large hole is provided as against a small opening in the base or side, since the lighting of the heater is usually 75 done in the darkness of the night.

There are certain proportion limitations also which apply to a heater of the character involved. The fuel charge must be of the right shape to permit its burning at the proper rate, that is, it must be relatively long, rather than spread out. The proportions which I have found to be satisfactory are: In a heater of thirty inches height, the diameter should be about ten and one-quarter inches 85 at the base. Experience has proven that the fuel charge, ordinarily of a quantity to run the heater for three hours, is properly disposed in such a proportioned heater to work most efficiently. The coal briquettes herein 90 considered, which are those in common use for general heating on the Pacific Coast, for about forty percent of their burning period supply a preponderance of volatile fuel, and for the remainder of their burning period 95 the combustion assumes more and more the form of incandescent glowing coke in a condensed and compact body, so that the thin metal is heated to a cherry-red. The proportions indicated provide a heater which effi- 100

ciently consumes fuel having the characteristics of the briquette just set forth.

A primary object of my invention is to provide an orchard heater which satisfies each and all of said conditions, and which is open throughout from end to end, i. e., is free of all obstructions of the character of grates, covers, supporting legs and kindling brackets, and in which the rate of burning is automatically controlled at the time of charging the heater, so that a heater is provided free of all mechanical devices such as drafts and dampers for regulating the rate of burning.

15 For the combustion of solid fuel, air must be admitted below the burning fuel to generate gases, and then air must also be admitted above the burning fuel to complete the combustion of the gases. The efficiency of the 20 heater depends upon the proper balance of these two factors, that is, the admission of air to the fuel chamber, and the admission of air to the gas combustion chamber. On the one hand, the admission of too much air to the 25 combustion chamber must be avoided to prevent the cooling of the heated gases which are of a combustion temperature and only need a little more oxygen to complete their oxidation, and yet the admission of such air must be sufficient to complete said oxidation of the 30 gases generated. The prevailing idea at one time was that smoke was desirable, but the bulletins of the Department of Agriculture, together with other authorities, all agree 35 that heat is to be desired rather than smoke. In fact, the chief item of cost of expensive heaters pertains primarily to the smoke eliminating feature. The carbon of the smoke is much more valuable in the form of heat. A 40 primary object of my invention is to provide an orchard heater which will cause complete combustion of the fuel and of the gases generated, so that a minimum of smoke results.

45 A further condition obtains which pertains to the gas combustion chamber in that for the most efficient operation there should be a progressive increase in the quantity of air admitted to said gas combustion chamber at different levels, to provide for the complete 50 combustion before said gases escape from the upper edge of the heater. While this might be readily accomplished by the employment of different sized openings, such a solution involves extra cost in manufacture. A primary 55 purpose of my invention is to provide such progressive admission of the quantity of air to the gas combustion chamber utilizing the same size of hole throughout the stove. This progressive influx of air in part results in my 60 invention by reason of the ratio of constant cross sectional area of air holes to the progressively changing cross sectional area of the combustion chamber of the heater due to its tapering design, being eight and one-quarter 65 inches in diameter at top.

Furthermore, a condition which must be provided for in a large number of heaters of the character herein described, which heaters are required for use for a given short season of the year only, is the condition imposed by the necessity of their handling, transporting and storing. Where a single grower may have some one to two thousand of such heaters to care for, the factor of storing, handling and transporting to and from the orchard is manifestly a very important element in the cost, and particularly is this so in view of the small margin of profit which now obtains in the fruit growing industry. The importance of all this is made very obvious by 80 reference to the fact that one user has actually in use eighteen thousand of the heaters embodying my invention of the specific design herein set forth.

85 A further condition to be satisfied is the re-fueling of the heater while in operation, if the period of heating is of such duration as to require such re-fueling. In other words, there must be a proper disposition of the air ports in addition to the requirements for 90 generating the gases and for the proper combustion of the gases above explained. Smoking and smouldering must be eliminated in a heater to meet the required conditions, and therefore a primary purpose of my invention 95 is to provide a heater having such disposition of air ports that the gases will not become too cold by the time that they reach the combustion chamber, but will be caused to burn promptly and thus prevent smoking and 100 smouldering.

In connection with repeated re-fueling, it becomes necessary to clear the fire-bed of ashes. In order to provide for an even burning temperature without attention from the 105 operator, I provide for the fire to burn from the upper portion of the charge downwardly. While this mode of operation is advantageous to provide a uniform burning rate, when such mode of operation is adopted with a grate in 110 the bottom of the heater, it so happens that very often there is a considerable unburned fuel next to the grate, which affords a serious obstruction to the removal of the ashes formed thereabove, i. e., such unburned coal is of a 115 size which will not pass through the grate openings, and it is difficult therefore to get the ashes to pass on through. Such unburned fuel may have already reached the coking stage when it is more or less impervious to the 120 ashes. A primary purpose of my invention is to provide for the elimination of the ashes and yet retain the unburned fuel for fuel purposes for continued burning.

125 The above mentioned general objects of my invention, together with others inherent in the same, are attained by the device illustrated in the following drawings, the same being merely preferred exemplary forms of embodiment of my invention, throughout which 130

drawings like reference numerals indicate like parts:

Figure 1 is a view in perspective of an orchard heater embodying my invention;

5 Fig. 2 is a view in longitudinal section of a heater embodying my invention, the front half being removed to show the disposition of the fuel and kindling within and the space left for the gas combustion chamber; and

10 Fig. 3 is a plan view of the metal blank employed to construct the heater embodying my invention.

The body 4 of the heater embodying my invention is constructed of thin sheet metal, 15 ordinarily 24 to 26 gauge. The requirement of cheapness and inexpensiveness of manufacture generally limits the construction material for a heater of the character described to such metal. This limitation is particularly 20 important since the device must have a form and proportion which will provide for the proper combustion of the fuel through its varying stages, i. e., while the fuel is giving off the volatile gas portion of its fuel properties as well as when it is burning as coke, 25 because if the heat is too great during the coking stage, or any other stage, it is manifest that the metal will be burned out.

That portion of the heater embraced with- 30 in the portion indicated at 5 represents the fuel chamber in the heater embodying my invention. The portion thereabove, and designated by the numeral 6, represents the gas combustion chamber. For the admission of 35 air below the burning fuel, I provide eight draft holes 7, 8, 9, 10, 11, 12, 13 and 14 on the level A. Other holes are disposed on the following levels and in numbers as follows: On level B four holes, namely, 15, 16, 17 and 40 18; on level C, one hole 19; on level D, one hole 20; on level E two holes 21 and 22; on level F, three holes 23, 24 and 25; and on level G, three holes, 26, 27 and 28.

The approximate location of these various levels may be as follows: Level A is approximately two inches above the bottom edge of the heater; B may be approximately six inches; C, approximately eleven and one-half inches; D, approximately thirteen and one-half inches; E, approximately sixteen inches; F, approximately twenty-one inches; and G, approximately twenty-five inches. These proportions have been found to give very satisfactory results. A change of more 50 than two inches, particularly in the lower levels of the holes, results in a very appreciably modified performance of the heater.

The function of the holes on level B will 60 be explained later. The hole on level C admits oxygen, the primary purpose of which is to start the oxidation or burning of the generated gases to which has been imparted a combustion temperature in the fuel chamber. Only one hole is provided at this level, so that 65 there will not be too great a cooling of these

gases; and, likewise, only one hole is provided on level D to carry said combustion on to a greater extent. The oxidation of the gases being thus commenced by the oxygen influx at C and D levels, the heat generated by said 70 oxidation next sets fire to or oxidizes a larger quantity of gaseous fuel, which requires a still greater influx of oxygen, when the same have reached level E, where two holes are provided. And as the gases reach level F, by the 75 same reasoning three holes are employed. Likewise, on level G for the same reason three holes are provided. The effectiveness of the holes on levels E, F, and G, and particularly on levels F and G, is influenced by the 80 tapering design of the heater. Manifestly, by the reduction of the cross sectional area, the three holes on level G admit a greater ratio of oxygen than is admitted on level F, and so on down. For the most efficient com- 85 bustion of the fuel, therefore, the tapering design is highly important to provide in part for this progressive influx of oxygen. Manifestly, such progressive influx results directly by reason of the ratio of constant cross sec- 90 tional area of the oxygen or air holes to the progressively decreasing cross sectional area of the combustion chamber as the gases proceed upwardly.

In the initial charging and burning of the 95 fuel, the four holes on the B level do not play an essentially important part, and for this reason, their function was omitted in the above description. However, when it becomes necessary to re-fuel the heater to prolong the 100 heating effect beyond that provided for the ordinary period, then the four holes on the B level become of great importance. For reasons herein explained, it is necessary to provide prompt ignition of the fuel in general, because the effectiveness of the heating must be immediate to provide for the sudden drop in temperature to render the heater effective in protecting the orchard. Upon re-fueling, it is a well known fact that the addition of new fuel tends to chill the fire and produce a smoking and smouldering condition because of such chilling. To overcome this, therefore, the four holes on the B level are 105 disposed to add the necessary oxygen in close proximity to the point where the new fuel will ordinarily meet the already burning charge, and thus provide the necessary oxygen to avoid said smoking and smouldering period. At least, such period is reduced to a 110 minimum, as the heater embodying my invention has proven in experience upon re-fueling to promptly burst into flame with the addition of new fuel, so that the smoking and smouldering period is practically eliminated, 115 and the full heating effectiveness of the fuel is maintained. If these holes, (four being found a satisfactory number), were not located on the B level, the escaping gases which 120 may start out at a combustion temperature 125 130

would soon become chilled by the fuel in the upper part and would escape unburned, and this would continue for some time until the heat generated would be so great that it 5 would cause all of said gases to burst into flame at the upper levels where the further admission of oxygen is provided.

By reference to the blank shown in Fig. 3, wherein appears the disposition of the holes 10 with respect to each other, it is manifest that they are in staggered relation, which disposition admits oxygen at the most advantageous points. This avoids too great an influx at one point which would obviously chill the heated 15 gases, and at the same time there must be a sufficient influx of oxygen to provide for the complete combustion of the gases as rapidly as possible, and to convert the carbon in the smoke into heat before its escape from the top 20 of the heater. Actual experience establishes the fact that heaters embodying my invention are practically smokeless, a fact substantiated by a report of the United States Weather Bureau Meteorologist.

25 In the device embodying my invention, the length of the burning period is determined by two factors,—first, the quantity of fuel charge, and, second, the position or location of the kindling as respects its level in the 30 fuel charge. As elsewhere pointed out herein, the conditions for protecting an orchard from frost when the trees are in full bud or bloom requires the prompt production of the heat. For this reason, slow igniting fuels, 35 such as charcoal, coke or carbon briquettes are highly undesirable and fail to meet the said requirement for promptness of providing heat to the endangered orchard. So complete is this failure that said fuel and the heaters designed to accommodate the same are not 40 used in the extensive fruit districts of the Pacific Northwest. Heretofore, carbon briquettes or coke, which are very slow in igniting, have been the preferred type of solid fuel for orchard heaters in the citrus fruit 45 sections. However, so desirable is the quick igniting that the heater embodying the invention herein set forth is rapidly supplanting the other types of heaters, even in the citrus fruit 50 sections. A further advantage of designing this heater to burn lump coal or coal briquettes is that this type of fuel is very cheap, abundant and widely available. For example, carbon briquettes cost from twenty 55 to twenty-five dollars a ton, while coal briquettes, which the heater embodying my invention is designed to burn, cost only approximately ten to twelve dollars per ton. Thus, a 60 distinct line is to be drawn between the heater designed to use coke or carbon briquettes, and the heater designed to use lump coal or coal briquettes. The coal briquettes are largely composed of a fuel which is quickly rendered volatile and it is these volatile gases which my 65 invention employs to produce the quick igni-

tion,—these gases also providing initially an abundant heating effect for the heater until the briquette assumes the characteristic combustion of carbon or coke. That is, during the thirty to fifty minute period in which the carbon or coke is attaining an effective heat-producing condition, my invention is designed to utilize the gaseous content of the fuel to immediately render the heater an efficient heat-producer. Obviously, this results in providing a prolongation of the effective heat-producing period. The heater embodying my invention is, therefore, designed to utilize suitable coal or coal briquettes characterized by their quick igniting properties, which will insure the promptness of ignition requisite to supply quickly the necessary heat to protect the orchards from frost damage. Among other objections which obtain to heaters of the present design, there is one outstanding 85 objection, namely, their slow ignition.

While on the one hand it is thus important to provide for quick ignition, nevertheless the design of the heater must be such as to prolong the burning period and be capable of 90 being regulated as to its period and rate of burning. Coal briquettes having a uniformity of composition, size and shape, afford an excellent fuel, and the design of my heater is especially adapted to take advantage of their 95 properties. These features are the proper proportion of diameter to height of the fuel charge; the providing of a fuel chamber and a gas combustion chamber; the proper disposition of the drafts as respects the fuel chamber and the proper disposition of the air or oxygen ports as respects the gas combustion chamber; and also the disposition of the kindling in respect to the height of the fuel charge, which last feature results from the 100 method part of my invention. I have found that by changing the position, up or down, of the kindling intermediate the length of the fuel charge, I can predetermine the rate of 105 burning in the heater of my design. To prolong the period, I place the kindling very close to the top of the fuel charge, and know, for example, for a three-hour period, that eight briquettes should be placed above the kindling and eighteen below, amounting altogether to about sixteen pounds of fuel. To increase the rate of burning and to shorten the burning period, a larger proportion of the fuel should be placed above the kindling. 110

The heater of my design permits of the lighting of the kindling by merely dropping some burning oil from a lighting torch, which immediately sets the fuel charge to burning. Since this lighting may be done through the large opening in the top of the heater, the convenience of my design of heater is apparent, when it is remembered that the operation is done in the night time in the dark. 115

120 My form of design of heater is frusto-conical, so that said tapering, in addition to 125

providing for the efficient combustion of the fuel gases, as heretofore explained, also provides for the nesting of the heaters for handling, transporting and storage purposes. 5 The bead 29 prevents the heaters from becoming wedged within each other, and insures their ready separation, even after being stored for nine months or more of the year, and when a great superimposed number 10 is placed upon any given one.

The heater embodying my invention is free of all obstructions. By this is meant that it is free of crates, covers, legs and internal brackets which would prevent nesting. Thus, 15 the absence of the grate has also this advantage, as well as the advantage of permitting the elimination of the ashes when it is desired to re-fuel. With the heater embodying my invention it is only necessary to rock the 20 same, and the ashes are caused to fall out around the lower edge of the base, leaving the unburned fuel intact.

My heater is, therefore, designed to overcome the difficulty incident to the cost and 25 operation of heaters with grates and utilize the ground as a grate in the sense that it supports the fuel and permits relative movement between the fuel support and the heater, thereby permitting the removal of this crust- 30 ed ash. That is, I move the heater by rocking the same instead of moving the grate. If it should become necessary to move the heater when charged, a heater embodying a grate would obviously permit its being readily carried and moved to another location. By providing my design of heater to operate with 35 suitable coal or coal briquettes, I am able to move the same by merely slipping a shovel or fork beneath the heater to hold the fuel 40 charged and proceed to any desired new location.

Moreover, the design of my heater further satisfies the requirement of convenience and 45 simplicity of operation by eliminating all mechanical devices to regulate the rate and period of burning, including re-fueling.

Where the weather conditions require only a relatively short period or an hour or two heating, I provide a heater of less capacity. 50 Instead of the thirty-inch length, this may be twenty-four inches, and in this design I reduce the number of holes in the gas combustion chamber and depress the holes on the other levels towards level A. Since the 55 initial fuel charge is reduced, this smaller design constitutes a more convenient and cheaper heater, and if the two sizes are employed in the same orchard, it is very readily determined in the dark in which heater 60 there has been provided the long period and the short period fuel charge. Naturally, where such smaller design is used, if it should develop that the burning period should be prolonged, then of course the inconvenience 65 of more frequent re-fueling arises.

The turned edge 30 on each side of the blank permits the two to be interlocked and these overlapping edges then spot welded, riveted, center punched, or otherwise held together. The ports or holes 7 to 28 are preferably one and one-quarter inch in diameter. 70

Obviously, changes may be made in the form, dimensions and arrangement of the parts of my invention, without departing from the principle thereof, the above setting 75 forth only preferred forms of embodiment.

The height may be varied from twenty to thirty-six inches and the diameter of the base may be varied from eight to fourteen inches. The number of one and one-quarter 80 inch ports above level A may be varied in the thirty-inch high heater herein set forth from eight to twenty; however, any departure from the number illustrated and described results in a decrease of efficiency. 85

I claim:

1. A lump coal or coal briquette burning orchard heater constructed of sheet metal, open and unobstructed throughout its length, the lower portion of which is used as a fuel 90 chamber and the upper portion as a gas combustion chamber, the lower edge of said heater resting in operation directly on the ground, said fuel chamber portion having air draft ports therein, and said gas combustion chamber portion having means for the admission of air in progressive quantities thereto per unit of volume from the bottom upwardly. 95

2. A lump coal or coal briquette burning orchard heater of frusto-conical form constructed of sheet metal, open and unobstructed throughout its length, the lower portion of which is used as a fuel chamber and the upper portion as a gas combustion chamber, the lower edge of said heater resting in operation directly on the ground, said fuel chamber portion having air draft ports therein, and said gas combustion chamber portion having means for the admission of air in progressive 100 quantities thereto per unit of volume from 105 the bottom upwardly. 110

3. A lump coal or coal briquette burning orchard heater constructed of sheet metal, open and unobstructed throughout its length, the ratio of the base diameter to the height 115 being substantially in the range of eight to twelve inches for the base and twenty to thirty-two inches for the height, the lower portion of which heater is used as a fuel chamber and the upper portion as a gas combustion chamber, the lower edge of said heater resting in operation directly on the ground, said fuel chamber portion having air draft ports therein, and said gas combustion chamber portion having air ports therein. 120

4. A lump coal or coal briquette burning orchard heater constructed of sheet metal, open and unobstructed throughout its length, the height of said heater being twenty-four to thirty inches, and the base being about ten 130

inches in diameter, the lower portion of which heater is used as a fuel chamber and the upper portion as a gas combustion chamber, the lower edge of said heater resting in operation directly on the ground, said fuel chamber portion having air draft ports therein, and said gas combustion chamber portion

having six to twelve one and one-quarter inch (1 $\frac{1}{4}$ ") holes, said holes being arranged progressively in greater numbers at different levels from the bottom up.

In witness whereof, I hereunto subscribe my name this 11th day of February, 1926.

ARTHUR T. KARR.
